GRID SECTION

William Shaw and Eliot B. MacLean, Saco, Maine,
and Theophile R. Gregoire, Lowell, Mass., as-
signors to Saco-Lowell Shops, Boston, Mass., a
corporation of Maine

Application March 17, 1951, Serial No. 216,116

2 Claims. (Cl. 19—95)

1

This invention relates in general to textile fiber preparation, and more particularly to a novel grid section for a picker apparatus used in the opening and cleaning of textile fibers.

In opening and cleaning textile fiber, it has been the practice for many years to use a picker including a revolving beater within a suitable enclosure to beat the textile fiber supplied by a feed device, such as a pair of rolls or a single roll and a pedal, downwardly over a series of transversely extending grid bars in order to remove the impurities therefrom, the theory of operation of such pickers being that the relatively heavy impurities will thus be beaten out of the fiber and will fall between the grid bars into a collection chamber while the cleaned textile fiber, being relatively light, will be carried over the grid bars by the air currents set up within the picker apparatus by the motion of the revolving beater. A relatively strong air current is then commonly employed to carry the cleaned fiber from the grid bar section of the picker and convey it from the picker apparatus to the next following fiber preparation apparatus.

We have found that in the usual picker apparatus, as above described, the relatively strong air currents used to convey the textile fiber from the grid bar section of the picker apparatus for the most part pass inwardly and upwardly between the grid bars, in the opposite direction to the desired direction of travel of the impurities removed from the fiber, thus greatly reducing the removal of such impurities, particularly in the case of relatively light impurities which tend to travel with the air currents conveying the fiber.

We have further found that the arrangement of the grid bars in such an apparatus is extremely critical if the most advantageous cleaning action is to be secured, since not only does the setting of the grid bars affect the cleaning of the textile fibers by physical contact with both the fibers and the impurities to be removed therefrom, but the setting of the grid bars further has a great effect on the direction and strength of the air currents in the apparatus and thus upon the removal of relatively light impurities from the fiber.

The proper setting of the grid bars, furthermore, is dependent upon the particular nature of the fibers to be opened and cleaned, for instance, the optimum setting for short fibers will be different from that for long, and the setting will vary for different types of fibers. Thus the grid bar settings of a picker should preferably be adjusted for optimum cleaning of each type of fiber, and as a practical matter, it is further desirable that such adjustments be easy and quick to effect.

2

It is a primary object of our invention to construct a novel picker grid section in which the conveying and other air currents are controlled to greatly reduce the flow of air inwardly between the grid bars, and thus more completely to clean the fibers, particularly of the relatively light impurities, since such impurities will then pass downwardly between the grid bars into the collection chamber instead of being carried along with the fibers by air currents.

It is a further object of our invention to construct a novel picker grid section in which the setting of the grid bars is such as to physically contact in the optimum manner the fibers to be cleaned in order to more completely beat out the impurities from such fibers.

It is a feature of the picker-beater grid section of our invention that the setting of each grid bar as well as the setting of other parts which affect the cleaning of the fiber is easily adjustable so that the entire apparatus may be easily and quickly adjusted in accordance with the particular nature of the fiber to be opened and cleaned.

It is a further feature of our invention that it is adapted to be used on nearly any picker-beater of conventional type, thus it is not necessary to construct entirely new apparatus in order to take advantage of the improved cleaning action of the picker-grid section of our invention.

Further objects and features of our invention will be pointed out by reference to the following description of a preferred embodiment of our invention, when taken in connection with the appended drawings, in which:

Fig. 1 is a somewhat diagrammatic cross-sectional elevation of the novel picker-grid section of our invention, showing it in connection with a conventional picker;

Fig. 2 is an isometric view of certain parts of the picker-grid section of Fig. 1; and

Fig. 3 is an isometric view of certain other parts of the picker-grid section of Fig. 1.

Referring to the drawings, the picker includes a frame 10 on which is rotatably mounted a beater 12 in suitable bearings, said beater being adapted to be driven by any suitable means not shown. A suitable enclosure is preferably provided surrounding the beater 12, as is well known in the art. The beater 12, though illustrated as a pin beater having three beater arms, may be any other suitable form of beater, for instance, a blade beater may be desirable in some circumstances. A beater feeding device including a suitably driven feed roll 14 and a pedal 16 may be used to feed the cotton fiber to the beater 12.

In accordance with our invention we provide a grid section including a plurality of grid bars 18 of generally triangular cross-section mounted on frame 10 with their active edges generally concentric with the path of travel of beater 12 and closely adjacent thereto, said grid section being mounted relatively closely adjacent the feeding means below the feed means in the direction of travel of the beater blade (clockwise in the drawing). The longitudinal axes of the grid bars extend generally parallel to the axis of rotation of the beater feeding means for a part of the path of travel of the beater, said path being somewhat less than 90° and preferably between 30° and 60° as measured around the grid section from the first grid bar 18 around the path of travel of said beater. The active edges of said grid bars are thus in a curved plane concentric with the path of travel of beater 12.

In order to permit adjustment of the grid section, each grid bar is mounted in adjustably fixed position so that it may be adjusted about its longitudinal axis as well as radially of the beater and the curved plane formed by the active edges of the grid bars. The mounting means, best shown in Fig. 2, comprises a pair of brackets 20, one on each end of a grid bar and having a hole 22 for receiving the stub shafts 24 on each of the ends of a grid bar 18. The brackets 20 are further provided with slots 26 extending from said holes 22 through one side of said brackets. Set screws 28 are provided in said brackets 20 to permit the sides of said brackets 20 on opposed sides of the slots 26 to be moved toward one another so that stub shafts may be securely clamped in holes 22. The brackets 20 are mounted in tracks 30 on a pair of cheek members 32 on opposite sides of said frame 10, said tracks extending generally radially of the axis of rotation of the beater. Set screws 34 are provided extending through holes 36 in said brackets and slots 26 at the bottom of tracks 30 in said cheek members to permit clamping the brackets 20 to the cheek members 32.

The cheek members 32 are adjustably mounted on opposite sides of frame 10 to support the grid bars extending generally between said cheeks by means of cheek mounting elements 40, said cheek mounting elements including in general two portions which slide at right angles to one another, the outer portions 42 sliding in tracks 44 on cheeks 32 and the inner portions 46 sliding on tracks 48 on outer portions 42, thus providing a universal adjustment of said cheek members in a plane corresponding to the side of frame 10 of the picker. The inner portions 46 are provided with holes 50 to receive set screws 52 by means of which inner portions 46 may be clamped to the frame 10 and simultaneously clamp inner portions 46 to the outer portions 42, the latter being thus clamped to the cheek members 32. We prefer that two of said cheek mounting elements 40 be provided on each cheek to enable suitably rigid mounting for each cheek 32 on the frame 10 of the picker.

A baffle plate 54 forming a part of said grid section is mounted in adjustably fixed position on cheeks 32 and extends between said cheeks closely adjacent the path of travel of beater 12 and closely behind the last grid bar 18. The plate 54 is provided with stub shafts 56 on opposite sides thereof and is preferably mounted by means of a pair of brackets 20 as hereinbefore described in order to permit rotational as well as radial adjustment of said plate. We prefer

that said baffle plate 54 have generally the form of a curved plane concentric with the path of travel of the beater 12.

5 A bottom plate 60 also forming a part of said grid section preferably mounted on cheeks 32 and extending therebetween behind the baffle plate 54 and spaced from said baffle plate extends in the direction of travel of the beater 12 toward the output end of said beater and preferably contacts the surface 62 forming the bottom of the air conveyor trunk leading from the picker. The plate 60 may be adjustably mounted in fixed position on cheeks 32 by means of brackets 64 and set screws 66 so that the end of the bottom plate 60 which contacts the trunk 62 may be raised or lowered to engage the bottom of trunk 62.

In the operation of our novel grid bar section, the fiber to be opened and cleaned is fed by said feed roll 14 (rotating clockwise as shown in the drawing) to beater 12. Beater 12 then beats the fiber downwardly over grid bars 18, said grid bars serving physically to contact the fiber and dislodge the impurities therefrom. The freed impurities are then thrown by centrifugal force through the space between the grid bars 18 while the light cleaned fiber is carried over the surface of said grid bars by air currents set up by the rotation of the beater. The air current set up by the beater over baffle plate 54 is relatively low 20 in velocity, but serves to carry the fiber into the relatively strong air current emerging through the slot provided between baffle plate 54 and bottom plate 60, said slot being nearer to the output trunk 62 than are the spaces between the 25 grid bars 18 thus providing a shorter and easier passage for the conveying air current than between grid bars 18. The air currents which tend to pass inwardly between grid bars 18 will thus be limited to relatively low velocities and will 30 not prevent the light impurities which have been beat out of the fiber from falling downwardly 35 between the grid bars into the collection chamber. 40

The individual adjustment of grid bars 18 as 45 well as plate 54 permits rotation of the grid bars and the baffle plate 54 about their longitudinal axes as well as movement of each of said grid bars radially of the path of travel of the beater 12. Thus the apparatus may be quickly and 50 easily adjusted for optimum cleaning of the particular fiber to be opened and cleaned. In practice, the first grid bar can be set furthest from the path of travel of beater 12 and each succeeding grid bar set closer to the path of travel of the beater in order to most effectively clean the fiber.

55 We have found that by far the greatest portion of the opening and cleaning of textile fibers takes place in the first portion of the grid section immediately following the input end thereof at the roll 14 and pedal 16 and have thus in effect 60 eliminated all but the first few grid bars, providing a baffle plate 54 following and closely adjacent to the last grid bar in place of the eliminated grid bars to control the air currents and thus the movement of the fiber. Baffle plate 54 65 serves the additional function of greatly limiting the air currents which pass inwardly between the grid bars and which would otherwise prevent the finer impurities from being thrown out, since a slot is provided between the baffle plate 54 and the bottom plate 60 through which the major portion of the conveying air may flow. The combination of plate 54 and the slot provided behind 70 said plate thus controls the air currents which formerly prevented the removal of relatively light impurities by providing a relatively unrestricted 75

path for the major portion of the conveying air. At the same time the relatively few grid bars 18 provide cleaning equal to that of a much larger number of grid bars, since they are situated in the first 30 to 60° of the path of travel of the fiber around the grid bar section of the beater and further provide improved removal of light impurities from the fiber due to the substantial reduction of the velocity of the air currents flowing inwardly between the grid bars, since such air currents have been largely diverted from the grid bars by the slot provided behind baffle plate 54.

For complete adjustability we prefer to mount cheeks 32 as hereinbefore described so that the grid bars as well as baffle plate 54 may be moved as a unit in any direction, thus permitting radial as well as circumferential adjustment of the unit. The bottom plate 60 is preferably also adjustable to provide a relatively close connection between the end of said plate and the conveying trunk 62 to prevent a slot therebetween and the consequent reduction in efficiency in the conveying air.

It will be thus seen that we have provided a novel picker-grid section in which increased control of air currents and complete adjustability of the grid bars provide a much improved cleaning and opening action on fibers, particularly in regard to the removal of light impurities from such fibers, and one which is easily added to existing pickers. It will be obvious to those skilled in the art that modifications of our invention may be made within the spirit thereof and the scope of the appended claims.

We claim:

1. In a picker apparatus having a rotatable beater, a grid bar assembly comprising a pair of spaced cheek members adapted to be mounted in the picker apparatus, a plurality of grid bars extending between said cheek members, individual opposed bracket means positioned on said cheek members, each of said means clamping and supporting an end portion of a grid bar for individual adjustable rotatable movement about its longitudinal axes, all of said bracket means being mounted on said cheek members for individual adjustable radial movement with respect to the path of travel of the beater, and means for securing said bracket means in their adjusted positions.
2. In a picker apparatus having a rotatable beater, a grid bar assembly according to claim 1 further including adjustable means for mounting each of said cheek members in adjustable relation relative to the rotatable beater.
